UNITED STATES PATENT OFFICE.

ALFRED J. CARLIN, OF ST. PAUL, MINNESOTA.

NON-REFILLABLE BOTTLE.

1,340,373.

Specification of Letters Patent. Patented May 18, 1920.

Application filed February 17, 1917. Serial No. 149,345.

To all whom it may concern:

Be it known that I, ALFRED J. CARLIN, a citizen of the United States, residing at St. Paul, in the county of Ramsey and State 5 of Minnesota, have invented certain new and useful Improvements in Non-Refillable Bottles, of which the following is a specification.

My invention relates to improvements in 10 stoppers for non-refillable bottles and other vessels provided with a neck. Such stoppers are designed for the purpose of allowing the liquid contents of the bottle to be poured out, while preventing the bottle from 15 being refilled after the original contents have been withdrawn.

Among the objects of the present invention are to provide an improved stopper of 20 that general character which shall be cheap and simple in construction, and interpose as little obstruction as possible to the free out-pouring of the contained liquid, and wherein the valve will be very sensitive and quick to close under the pressure of any 25 liquid attempted to be forced or poured into the bottle, and will be protected from being tampered with.

To these ends the invention consists in the construction, combination and arrangement 30 of parts hereinafter described and claimed.

In the accompanying drawings showing an embodiment of the invention,

Figure 1 is a central vertical section 35 through the improved stopper and a fragment of the neck portion of a bottle in upright position;

Fig. 2 is a similar section with the bottle decanted for pouring out the contents;

Fig. 3 is a horizontal section on line 3—3 40 of Fig. 1;

Fig. 4 is a perspective view of the ribbed gravity-cap that rests upon the valve, and

Fig. 5 is a view partly in section and partly in elevation of the valve and gravity- 45 cap.

As shown in the drawings the improved stopper comprises a tubular cap or casing 2 which may be of porcelain or other suitable material, and which incloses the valve 50 elements of the stopper. The cap is constructed to rest or seat upon the outer end of a bottle neck 3 or upon an annular washer 4 of cork or other resilient material interposed between the cap and the end of the 55 bottle neck. The interior bore of the cap is

cylindrical and of uniform diameter and of substantially the same diameter as the interior of the bottle neck, and it has at the top a central pouring opening 5 of lesser diameter. Near the bottom it is formed with a circumferential exterior shoulder 6, whereby it may be secured to the bottle neck by means of a sheet metal collar 7 crimped over the shoulder and bent or spun into a groove 8 on the outside of the bottle neck.

In the bottom of the cap is a seating ring 9 for the valve. The edge of the ring fits into a circumferential groove or notch recessed into the lower end of the cap wall, and the ring is held between the shoulder 60 10 which forms the top of the groove and the washer 4. It has a central tubular downward extension 11 which fits within the bottle neck, and is formed with a central hole or opening 12 through which the contents of the bottle can be poured out when the bottle is inverted or decanted, as shown in Fig. 2.

Loosely arranged within the cap 2 above the ring 9 and normally seating thereon is 80 a valve disk or block 13 of some light material, preferably cork, of larger diameter than the opening 12 in the ring, so that the valve, when centered within the cap, will close the opening. To assist in holding the 85 valve down upon its seat I have provided a gravity cap or thimble 14 of uniform diameter which rests upon the top of the valve when the bottle is in upright position. This is provided peripherally with straight spacing ribs or legs 15 of parallel width which extend down upon the outside of the valve disk and serve to confine it and keep it centered so that it will not become tilted or tipped and thereby seat imperfectly. These 90 ribs extend almost or quite to the wall of the cap 2 so that the cap 14 will itself be centered and guided by them in its movements up and down. In order that the weight of the cap may all come upon the 100 valve 13 when the bottle is in upright position I have made the legs or ribs too short to reach the ring 9.

The spaces between the legs or ribs 15 form straight vertical ports through which 105 the liquid can pass out through the bottle neck when the bottle is decanted or inverted. In order that the liquid may have a free straight passage from these ports over the top of the cap 14 and out through the cen- 110

tral pouring opening 5, I have provided the top of the cap near the periphery thereof with a plurality of spacing lugs 16 which keep the top of the cap from closing the opening 5.

It will be noted upon inspection of the drawings that the parts are particularly constructed to effect a noiseless telescopic movement of the gravity cap and valve block within the uniform bore of the cap, which prevents undesirable rattling when the bottle is decanted.

In operation, when the bottle is standing upright, as shown in Fig. 1, the valve 13 will seat upon the ring 9 and close the central opening 12 so that no liquid can pass into the bottle and the valve will be held down firmly upon its seat by means of the gravity-cap 14. When the bottle is inverted or decanted to pour out the contents, as illustrated in Fig. 2, the gravity-cap and valve will both drop away from the ring 9 toward the mouth of the bottle until the lugs 16 lodge against the upper wall of the cap 2, thereby uncovering the valve opening and allowing the liquid in the bottle to pass out therethrough into and through the peripheral ports between the legs 15 of the gravity-cap and over the top of this cap between the lugs 16 to the pouring opening 5.

If it is attempted to refill the bottle when the same is in upright position, as shown in Fig. 1, the liquid will merely fill the ports and spaces outside the gravity cap 14 and the valve 13, but cannot pass through the valve opening 12 because that opening will be covered and closed by the valve 13. The liquid cannot lift the valve from its seat in spite of its buoyancy on account of the downward pressure exerted thereon by the gravity-cap and by the liquid on top of the same.

Should it be attempted to force liquid into the bottle by pressure when the same is inverted or decanted, the liquid will force the cork valve up, or cause it to float up, so as to seat against the ring 9, and close the opening 12 therein, the tendency of the valve to rise to the top of the liquid being reinforced by the direct pressure of the liquid on the under side of the valve. To allow this pressure to be exerted on the valve the under edges of the cap 14 between the legs 16 are cut away as shown at 17 so that the

liquid will impinge upon the outer edge of the valve.

While I have here shown a specific embodiment of the invention, it will be understood that the details of the structure can be changed and modified in various particulars without departing from the principle of the invention, the scope of which is defined in the claims.

1 claim:

1. A non-refillable bottle including a neck portion formed with a discharge opening therethrough, and means for closing the discharge opening comprising a cork body for seating over the latter and a gravity cap seating on the cork body and having depending legs guidingly embracing the side of the latter for a portion of its thickness and guidingly fitting the interior of the neck portion.

2. A non-refillable bottle having a neck, a tubular casing seating thereon and provided with a discharge opening and an inlet opening, a gravity cap slideable within the tubular casing and formed with depending legs, the alternate ones of which extend above the cap and are adapted to abut the end of the casing to prevent closing of the discharge opening, and a valve block embraced by the downward leg extensions and adapted to seat over the inlet opening of the casing.

3. A non-refillable bottle having a neck, a tubular casing seating thereon and contracted at one end to form an end wall with a discharge opening therethrough, an inlet opening for the casing, a valve block of light fibrous material engageable over the inlet opening to close the same, and a holder for the block seating on the same and having depending legs guidingly embracing the periphery of the block to secure the same thereto, the latter projecting beyond the legs to be uninterrupted thereby during the seating of the block, the alternate legs extending above the body of the holder to abut the end wall of the casing when moved toward said wall.

In testimony whereof I affix my signature in presence of two witnesses.

ALFRED J. CARLIN.
